HAIR WAVER OR CURLER

Hannah Chisholm Fraser and Mary Ann Fraser,
Bournemouth, EnglandApplication December 15, 1931, Serial No. 581,136,
and in Great Britain December 20, 1930

6 Claims. (Cl. 132—44)

This invention relates to rubber or like hair waving or curling devices of the kind having an eye or equivalent at one end of the body portion through which the other end of said body portion is adapted to pass after flexing or bowing the device and be locked by the inherent resiliency of the device.

Very often when the hair is being wound round the shank as in a device of the aforesaid kind, the initial coil of hair slips over the head prior to bowing and locking the device. The object of the present invention is to provide an improved construction of hair waving and curling device of the aforesaid kind, and in particular, to provide such a device which will prevent the initial coil of hair slipping over the head prior to bowing and locking.

Preferably in accordance with the present invention a device of the kind aforesaid comprises a tongue piece at one end of said shank, and an apertured head at the other end of said shank extending in a plane different from that of the shank, said head preventing the hair slipping off the device over said head.

The head may be round, square, hexagonal, oval, elliptical, diamond-shaped, or in fact of any other shape as may be found desirable or advantageous, and its edge may be plain or undulating. Moreover, the eye or aperture may or may not conform to the shape of the head.

The other end of the device, which as already stated, is adapted to be pushed through the eye or equivalent and be locked by the inherent resiliency of the device, may be formed as a tongue-piece of any suitable shape but is preferably tapered or substantially ovoid, oval, elliptical or diamond-shaped, with or without an aperture or apertures to facilitate its contraction in passing through the eye, and with or without undulations in its edges. When such an aperture is provided, it also may be of various shapes and may or may not conform to the shape of the tongue-piece itself.

In some cases the tongue-piece may terminate in at least one sphere or ball or partial sphere which may be perforated, adapted to be pushed through the eye or equivalent under contraction and then to exert a locking action preventing its accidental withdrawal.

We may make our waver or curler with a head or equivalent as illustrated in any of the figures hereinafter referred to, but with a ball or swelling or enlargement of any suitable shape at a short distance from the other end of the shank so as to leave a projecting point which will facil-

tate entry through the aperture in the head or equivalent, this ball or swelling or enlargement being such as to assist the locking action.

We wish it to be understood that the head of the device extending in a different plane from that of the body portion, may be located at one end of the device or at some little distance from that end. The head also serves as a finger grip in the application of the device; and owing to the head of the waver being normal to the shank it provides a much more secure grip than is obtainable in the case of a flat waver. With the normally disposed head of our waver, the fingers are free to control any wriggling of the rubber shank of the waver and the resiliency being thus held in check, the hair can be more quickly and easily coiled on the shank and the waver secured in position without any tendency for the waver slipping out of the fingers and disappearing under the hair. When it is located at some little distance from the end of the shank, the projecting portion of the shank assists the locking action and may constitute the said finger grip.

However in a device as constructed in accordance with this invention, the shank may be provided with a slit in known manner for the purpose of enabling it to be used as a curler as well as a waver. When no slit is provided the device will be suitable as a waver only.

Now, merely by way of example and without intending any restriction, we have illustrated certain constructional forms of our device on the accompanying drawing, whereon:

Fig. 1 is a perspective view of one form made of rubber in which the head is integral with the shank;

Fig. 1a is a modification of Fig. 1;

Fig. 2 is a similar view of a second form having the head integral with the shank;

Fig. 3 shows, in front and side elevation respectively, a third form also having the head integral with the shank;

Fig. 4 is a perspective view similar to Fig. 1, showing how the aperture through the head may be nicked or serrated or slotted for a purpose hereinafter stated;

Fig. 5 is a perspective view of another form in which the head is in the form of a half ring.

Fig. 6 shows in front elevation and side elevation another form in which the head is attached to the shank;

All the constructional forms illustrated are made of rubber.

In the form illustrated by Fig. 1, the head 1 extends normal to the integral shank 2 at one

end thereof and in substance is a ring through the aperture 4 of which the other end of the shank or tongue-piece 3 having a swelling 3a is adapted to be pushed after flexing or bowing 5 the device. The shank is slit at 5 to enable the device to be used as a curler as well as a waver.

In Fig. 1a the shank is extended at 2a to improve the locking effect on the tongue piece.

To use the device just described as a waver, 10 it is held by the head 1 flat against the scalp, and with the opposite end of the shank or tongue-piece 3 slightly raised off the head to facilitate the winding of the coil of hair to be waved on the shank. The initial coil of hair is then wound 15 on to the shank and pressed against and imprisoned by the normally disposed head, and it will be at once apparent that during this process the head 1 acts as an abutment, projection or stop which positively prevents the hair from slipping 20 thereover. After the coil of hair has been wound on to the shank, the shank is flexed or bowed and the tongue-piece 3 pushed through the aperture 4 in the head 1 whereupon it is locked in that 25 position by the inherent resiliency of the device, and swelling 3a. With a waver having a normally disposed head as above described, there is no danger of the hair being pushed right off the head of the waver and thus the user can start to coil the hair right up against the head of the 30 waver and not half-way down the shank as is necessary in the case of a flat waver. Moreover, owing to the firm grip which can be obtained of the normally disposed head in our 35 waver, it is possible to wave the hair very close to the scalp, and there is no danger of the resiliency of the rubber shank causing the head of the waver to slip through the fingers.

To use the device as a curler the ends of the wisp of hair are inserted through the slit 5 and 40 thereafter the device is turned in the fingers towards the head so as to roll the wisp of hair on the shank 2. Finally, the shank is bowed and the tongue-piece 3 pushed through the aperture 4 in the head 1 and locked by the inherent resiliency 45 of the device, as already stated.

In the construction according to Fig. 2 the tongue-piece 3 of the shank 2 terminates in a hemispherical portion or swelling 6 which can be pushed through the aperture 4 in the head 1 after the device is flexed or bowed, but which 50 presents the shoulders shown to assist the locking action. These shoulders prevent a too easy or accidental withdrawal of the tongue-piece and the portion 6 from the aperture 4 in the head 1.

Fig. 3 shows a construction in which the tongue-piece 3 is made substantially ovoid for the purpose just mentioned, this tongue-piece, however, having an aperture 7 which enables the tongue-piece to be easily contracted and pushed through the aperture 4 in the head, but the shoulders between the tongue-piece and the shank 2 are then set to prevent accidental or 60 too easy withdrawal of the tongue-piece from the aperture.

If desired, the wall of the aperture 4 in the head 1 in any of the constructional forms so far described may have any number of nicks or serrations 5 as illustrated by Fig. 4 for the purpose of facilitating displacement of the said wall in the passage of the tongue-piece 3 through the aperture.

According to Fig. 5 the shank has two lateral projections 1a, and into these projections a half ring 1 is secured. The tongue piece 3 is adapted

in the manner already described to be pushed through the aperture 4 in the half ring.

In the construction according to Fig. 6 the tongue-piece 2 is enlarged at one end 2a and this enlargement is adapted to receive a ring 1 80 constituting the head or stop for preventing the hair slipping over the head. The side edges of the enlargement 2a are checked or cut out and the ring 1 is sprung over the enlargement 2a into engagement with said recesses, being thereby retained in place. Obviously, the shank can be bowed to one side or the other and the tongue-piece 3 threaded through the aperture 4 in the ring 1 at one side or other of the shank. In this construction the enlargement 2a may constitute 85 a finger grip during the application of the device. Moreover, after the tongue-piece 3 is passed through the aperture 4 in the ring 1, it bears frictionally against the enlargement 2a and thereby assists the locking action. 90

Instead of a ring 1 a half ring or loop may be employed.

From the foregoing it will be apparent that we prefer to provide the eye or aperture 4 through which the tongue-piece is pushed in the 100 head or ring 1 that extends normal or oblique to the plane of the shank, but if desired the said eye or aperture may be provided in the shank itself adjacent the head. Where as in Figs. 5 and 6 the ring or head is attached to the shank, said 105 ring or head may be of metal, rubber, bone or other material.

In some cases we may form the body portion or shank with side fins; and we may furnish the eye or aperture 4, whether it be in the head or in 110 the shank, with an eyelet of metal, celluloid or the like. Further, the shank may be of wavy or undulating shape. The cross-section of the shank may be round, square, oval, flat, or otherwise. 115

The head and tongue piece may be detachable from the shank so that any head and any tongue piece may be used together, while the heads or rings may be made of relatively soft rubber and the shanks of relatively hard rubber. 120

While we have described and illustrated certain embodiments of our invention we intended no limitations other than those imposed by the scope of the claims that follow, since it is obvious that many modifications, some of which 125 are herein indicated, can readily be made without departing from the scope of the invention.

We claim:—

1. A hair waving or curling device comprising a shank, a tongue-piece at one end of the shank, a head having an aperture therein through which said tongue-piece is adapted to be passed, and means whereby said head is rigidly united to said shank so that the axis of said aperture maintains a parallel or substantially parallel relationship with said shank even with said tongue-piece in said aperture said head constituting a rigid hair retaining abutment and finger grip for said shank. 130

2. A hair waving or curling device comprising a resilient shank, a resilient tongue piece at one end of said shank, and a resilient head having an aperture therein and integrally united with said shank so that said head has the plane of its aperture permanently normal to the adjoining part 135 of said shank and constitutes as a whole a stiff normal projection close up to which hair can be coiled and firmly pressed without slipping off said shank. 140

3. A hair waving or curling device comprising 150

a rubber shank, a rubber tongue-piece at one end of said shank, and a rubber head having an aperture therein and integrally united to the other end of said shank at or about right angles thereto so that said tongue-piece when inserted through said aperture lies substantially flat on the scalp, and said head can be firmly gripped and held close to the scalp by the user.

4. A device as claimed in claim 2, in which the 10 wall of the aperture in the head is nicked or ser-

rated in order to facilitate passage of the tongue piece therethrough.

5. A device as claimed in claim 2, in which the tongue piece has an enlargement at its end.

6. A device as claimed in claim 2 in which the 80 head is of relatively soft rubber while the shank is of relatively hard rubber.
